UNITED STATES PATENT OFFICE.

EDWARD L. CORMAN, OF UPLAND, CALIFORNIA.

FUEL-CONTROL MECHANISM FOR INTERNAL-COMBUSTION ENGINES.

Application filed November 20, 1926. Serial No. 149,728.

This application relates to improvements in fuel control mechanism for internal combustion engines and has for its primary object to provide an auxiliary control for the 5 throttle valves of tractors and light engines.

A further object of the invention is the provision of a control mechanism which will permit more accurate adjustment of the fuel supply valve of an internal combustion engine. 10

A still further object of the invention is the provision of a mechanism of the above character which can be readily mounted for operative movement to control the fuel supply valves of tractor engines and the like. 15

Still another object of the invention is the provision of a mechanism of the above type, which is simple and durable of construction, efficient in use and which can be manufactured at a comparatively low cost. 20

Other objects and advantages of the invention will become apparent as the description progresses.

In the accompanying drawing, forming 25 a part of this specification, and in which like reference characters are employed to designate corresponding parts throughout the same:

Figure 1 is a front elevational view of a 30 control mechanism constructed in accordance with my invention,

Figure 2 is a horizontal transverse sectional view taken on the line 2—2 of Figure 1, and

Figure 3 is an end elevational view of the 35 control mechanism.

Referring to the drawing, wherein for the purpose of illustration is shown the preferred embodiment of my invention, the 40 numeral 10 designates a fragmentary portion of a tractor instrument board upon which is securely fixed a suitable fuel valve control. At the present time, the throttle control of tractor engines, particularly upon 45 a well known type of tractor, embodies a toothed quadrant plate secured to the instrument board to which is operatively secured a control lever. The control lever is formed with a spring pressed trigger adapted to engage the teeth of the quadrant to permit 50 adjustment of the lever in any suitable position. It has been found that this particular control structure is not sufficiently delicate and accurate as it is often desirable to secure 55 a more delicate adjustment for the proper operation of the engine. With this in mind,

I have modified the standard construction of the control and supplemented the same with an auxiliary adjusting mechanism which will provide a more delicate and accurate 60 adjustment of the throttle.

Referring more particularly to the structure embodied in my invention, the numeral 11 indicates an arcuate substantially quadrant shaped support arm bent at its upper 65 end to provide a securing flange 12 which is screwed or otherwise fastened to the instrument board 10, and likewise bent at its lower end to provide a flange 13. A straight supporting arm 14 projects horizontally 70 from the instrument board and at its outer end is connected with the flange 13 of the quadrant arm 11. The inner end of the arm 14 is bent to provide an attaching flange 15 which is fastened to the instrument board by 75 means of screws or the like, while the other end is bent at a right angle and carries an internally screw-threaded bearing collar 16. An intermediate spacing bar 17 is secured to the upper end of the arm 11 and adjacent 80 the inner end of the straight arm 14, this spacing bar being disposed in spaced relation to the instrument board. The lower end of the spacing bar 17 is twisted at a right angular position and formed with horizontally 85 projecting parallel bearing ears 18.

A quadrant plate 19 is mounted in vertical position against the curved arm 11, the outer curved edge of this plate being arranged to form ratchet teeth 20, extending in a substantially parallel position with the outer edge of the curved arm. This quadrant plate is spaced from the arm and is formed adjacent its lower forward edge with an arcuate slot 21. A pin 22 is secured to the curved arm 90 to project through the slot so as to limit the movement of the plate. The lower inner edge of the plate 19 is provided with a tapered downwardly extending finger 23, this finger being apertured at its upper and lower ends. 95 The upper apertured end of the finger is adapted to register with the openings formed in the bearing ears 18, a pivot pin 24 extending through the openings to provide a pivot joint. 100

The throttle valve is normally controlled by movement of a tapered control lever 25 the upper end being offset to provide a handle 26 while the lower end is formed with an apertured extension adapted to engage the 110 pivot pin 24. This lever is formed with a substantially right angular lever arm 27, the

outer end of which is apertured to engage the inner end of the throttle lever 28. The outer free end of the lever is provided with a spring pressed pin 29 which is normally urged into engagement with the ratchet teeth 20 so as to maintain the lever securely in any set position.

My improved structure aims to provide means whereby the entire plate and lever 30 may be adjusted to control a throttle valve, this being effected by means of a circular screw-threaded rod 30 threadedly projected through the horizontal collars 16 and horizontally movable therein. Secured to the outer end of the rod 30 is a hand wheel 31 adapted to permit convenient adjustment of the rod. A horizontal connecting bar 32 is pivotally connected with the lower end of the finger 23, as at 33, while the outer end of the bar is bent at right angles to provide a bearing for the inner end of the rod 30. The rod is projected through the bearing 34 and rotatably held in position thereon by means of collars.

It will thus be apparent that by rotation of the hand wheel 31 the rod 30 and bar 32 will be horizontally reciprocated and impart swinging movement to the finger 23 and plate 19. Swinging movement of the plate will cause a similar swinging movement of the lever 25 for operation of the throttle valve. The initial throttle control setting is obtained by adjustment of the lever 25 relative to the plate 19. A more accurate and

finer adjustment may be then had by operation of the hand wheel 31, which will swing both the lever and plate 19. In this manner, a more accurate and economical fuel control is obtained whereby tractor operation can be more effectively controlled.

It is to be understood that the form of my invention herewith shown and described is to be taken as the preferred example of the same, and that various changes as to the shape, size and arrangement of parts may be resorted to without departing from the spirit of the invention or the scope of the subjoined claim.

Having thus described my invention, I claim:

A control mechanism for operating the throttle valve of internal combustion engines comprising a support for attachment to an instrument board, a plate pivotally mounted on the support for swinging movement, a control lever pivotally mounted upon the plate and having an extension arm connected to the throttle extension rod, the said lever being adjustable independently of the plate and embodying locking means for engagement therewith, and an auxiliary control mechanism operatively connected with the plate and adjustable to swing the plate and control lever simultaneously to permit accurate adjustment of the throttle valve.

In testimony whereof I affix my signature.

EDWARD L. CORMAN.
